(57) **CLAIM**

The ornamental design for a sprayer frame, as shown and described.

DESCRIPTION

FIG. 1 is a front left isometric view of a sprayer frame;
 FIG. 2 is a rear left isometric view thereof;
 FIG. 3 is a left side view thereof;
 FIG. 4 is a front view thereof;
 FIG. 5 is a right side view thereof;
 FIG. 6 is a back view thereof;
 FIG. 7 is a top view thereof;
 FIG. 8 is a bottom view thereof; and,
 FIG. 9 is a right side view of the claimed design in the condition of use.
 The broken lines are indicative of unclaimed portions of the design.

1 Claim, 9 Drawing Sheets(56)
